DISPENSING APPARATUS

George A. Blake, New Bedford, Mass.

Application January 29, 1932. Serial No. 589,713

6 Claims. (Cl. 312—63)

This invention relates to dispensing devices and more particularly to devices of this character which are adapted to deliver articles or packages of merchandise such, for example, as candy, chewing gum, cigarettes, handkerchiefs, or other goods which may be wrapped or packed in cartons of a size adapted to be conveniently handled by such a machine.

The general object of the invention is to provide a dispensing device of this type which is of simple and improved construction, requiring a minimum number of parts, which is easy to operate, and which may be adapted for the display and dispensing of a great variety of articles or packages.

Another object is to provide a dispensing device which is adapted to be operated from the rear by a clerk or salesman so as to eject or deliver an article or package from the front of the device onto the counter or into the customer's hands, whereby the operating means are not readily or conveniently accessible to the customer. In this way the vendor has control over the dispensing of the goods and losses due to unauthorized operation of the machine, and theft of the contents thereof is minimized.

A further object is the provision of a machine of this type which comprises a cabinet within one portion of which a supply of superposed articles or packages of merchandise is adapted to be displayed and into a lower portion of which is adapted to be installed a dispensing mechanism for successively ejecting the articles from the bottom of the pile.

A still further object of the invention is to provide an ejector of the type described which is provided with alternative operating means, one of which is adapted to be struck or pushed and the other is adapted to be pulled in order to cause the ejector to discharge the articles.

Other objects and features of novelty will be apparent from the following specification when read in connection with the accompanying drawings, in which one embodiment of the invention is illustrated by way of example.

In said drawings:

Figure 1 is a view in front elevation of a dispensing cabinet embodying the principles of my invention;

Figure 2 is a view thereof in rear elevation;

Figure 3 is a view in horizontal cross section taken on line 3—3 of Figure 2;

Figure 4 is a fragmentary vertical cross sectional view on an enlarged scale of the lower por-

tion of the cabinet showing very clearly the dispensing mechanism;

Figure 5 is a view in rear elevation of a modification of my improved dispensing device;

Figure 6 is a fragmentary vertical cross sectional view taken on line 6—6 of Figure 5; and

Figure 7 is a horizontal cross sectional view taken on line 7—7 of Figure 6.

In the embodiment of the invention illustrated in Figures 1—4, inclusive, the dispensing cabinet as a whole is designated by the numeral 10 and is provided with the side walls 11 and 12, the top 13, and the bottom wall 14. The cabinet may be constructed of wood, sheet metal, ply board, or any other suitable material. As shown in Figure 1, the larger part of the front surface of the cabinet is formed by the transparent panel 15 through which the articles or packages 16 may be viewed. The lower portion 19 of the front face of the cabinet is made of opaque material and is designed to conceal the ejecting mechanism. A discharge opening 20 is provided between the panels 15 and 19 through which the articles may be ejected.

Referring now to Figure 2 of the drawings, which is a rear view of the cabinet, the packages or articles 16 are retained by means of the flanges 22 which provide a rear wall for the display container portion of the cabinet. A filling opening 25 is provided at the top of the rear portion of the cabinet readily accessible only to the clerk or salesman. The rear wall flanges 22 terminate at a point opposite the lower end of the glass front panel, and the remaining lower portion of the rear wall is omitted so as to provide an opening for the insertion of the dispensing mechanism presently to be described.

One of the essential elements of the dispensing mechanism is the frame 27 which comprises the base 28, the two spaced parallel vertically extending members or partitions 29 and 30, and the outwardly extending flanges 31 and 32 secured at the upper ends of these partitions. The base 28 may be secured to the bottom wall of the cabinet by means of the screws or other fastening elements 34. The horizontal flanges 31 and 32 are adapted to form a shelf or support upon which the lowermost article or package is adapted to rest. The top surface of the shelf thus provided is, of course, flush with the upper edge of the front panel 19 forming the lower margin of the delivery opening 20.

The ejector member, which is adapted to push the lowermost article forwardly through the opening 20, comprises essentially the lever 35 of a somewhat irregular contour which is pivotally

mounted intermediate its length upon the trunnion or pin 36 which is secured at either end within openings formed in the partitions 29 and 30. A projection 38 is formed at the upper end of 5 the lever or ejector 35 which is adapted to extend above the shelf provided by the flanges 31 and 32 and to contact the rear end of the article or package to be delivered as at 39.

A rearward extension 40 is provided upon the 10 lever as one means for operating the same to eject an article. It will be apparent that when the portion 40 is pushed or struck, the upper end of the lever will move forwardly around the pivot 36 and sweep the lowermost package 16 from the shelf 15 and through the opening 20.

An alternative means for operating the device is provided in the chain 42 which may have a ball 43 at the end thereof and which is adapted to be connected to the lower portion of the lever as at 20 44. Since this point of connection 44 is below the pivot point 36, it is obvious that a rearward jerk or pull upon the chain 42 will cause the ejector to operate in the same way as by manipulation of the portion 40, as previously described.

25 In order to resiliently urge the lever 35 toward its retracted position, a coil spring 46 is provided, one end of which is secured to the cross pin 47 which extends between the forward wall portions of the partitions 29 and 30, the other end of this 30 spring being connected to the forward lower portion of the lever 35 as at 48. The projection 50 formed upon the lower outer end of the lever 35 is adapted to extend below the base 28 of the dispensing device and to abut the rear edge thereof 35 when the lever 35 is in the retracted position toward which it is urged by the spring 46.

It will be readily apparent that the distance through which the article or package is thrown from the device may be regulated by the force of 40 the blow upon the portion 40 or by the force of the pull upon the chain 42.

In the modification illustrated in Figures 5-7, inclusive, of the drawings, the cabinet or container 50 is substantially the same in construction 45 as the cabinet 10 illustrated in the first described embodiment. The rear wall 51 of the cabinet is provided with the upper filling opening 52 for the articles of merchandise 53 which are adapted to successively descend within the 50 container as they are ejected at the lower portion thereof. The rear wall 51 is also provided with a vertical slot 54 through which access may be had to the packages within the cabinet. The front wall 55 of the cabinet is preferably constructed of transparent material and is provided, as at 56, with a discharge opening through which the lowermost package may be ejected. In the lower portion of the rear wall 51 there is provided an opening 58 which is adapted to substantially register with the discharge opening 56 in the front wall.

In this embodiment there is provided an ejecting mechanism 60 which is disposed in the lower portion of the cabinet and provides a rest or 65 a shelf 61 for the packages or articles. This ejector mechanism 60, as illustrated, comprises a block of preferably rectangular cross section, within which is provided a preferably longitudinally extending cylindrical bore 63. A plunger 70 65 is adapted to be disposed for longitudinal reciprocation within this bore and is adapted to be urged toward its retracted position, as shown in Figure 6, by means of a coil spring 66 which is disposed forwardly of the plunger 65 and 75 is adapted to be compressed between the plunger

and the forward end 67 of the bore. Suitably secured to and projecting upwardly from the plunger 65 is the ejector arm 70. A slot 71 is provided in the upper surface of the block 60 to accommodate the reciprocating movement of the ejector arm 70 during the dispensing operation. Secured to the rear end of the block 60 as by means of the screws 73 is the plate 75 which serves as a stop or abutment for limiting the rearward movement of the plunger 65 and its ejector arm 70 under the influence of the spring 66.

80 From the foregoing description, it will be readily understood that, in operation, the rear end 77 of the plunger 65 is adapted to be struck or pushed in order to eject the article or package which is resting upon the shelf 61.

85 This invention thus provides a very convenient dispensing mechanism which is adapted to be so positioned upon a counter or similar support as to face the customer and to be operated from the rear by the clerk or salesman and by means of which an article may be delivered to the purchaser promptly without being handled by the clerk and without danger of theft. It is also 90 apparent that the dispensing device 27 of the first described embodiment may be built into a cabinet as an integral part thereof instead of being installed as a separate mechanism, as has been described in connection with the illustrated embodiment. Furthermore, various other changes and modifications may be made in the embodiment disclosed without departing from the scope of the invention as disclosed in the 95 following claims.

100 Having thus described the invention, what is claimed as new and desired to be secured by Letters Patent is:

1. In a dispensing device for articles of merchandise, in combination, a frame comprising a 115 base, a pair of spaced parallel vertical members extending upwardly from said base, a horizontally disposed shelf member extending outwardly from the top of each of said vertical members, and adapted to successively support said 120 articles, an ejector lever disposed between said parallel members pivoted at a point intermediate its length thereto, and adapted to move between said shelf members to discharge said articles from said shelf, and operating means for said 125 lever.

2. In a dispensing device for articles of merchandise, in combination, a frame comprising a base, a pair of spaced parallel vertical members extending upwardly from said base, a horizontally 130 disposed shelf member extending outwardly from the top of each of said vertical members, and adapted to successively support said articles, an ejector lever disposed between said parallel members pivoted at a point intermediate its length 135 thereto, and adapted to move between said shelf members to discharge said articles from said shelf, and a retracting spring connected at one end to said frame at a point in advance of said lever, and at its other end to a portion of said 140 lever below its pivot point, stop means for limiting the retraction of said lever by said spring, and operating means for said lever.

3. In a dispensing device for articles of merchandise, in combination, a frame comprising a 145 base, a pair of spaced parallel vertical members extending upwardly from said base, a horizontally disposed shelf member extending outwardly from the top of each of said vertical members, and adapted to successively support said articles, an 150

- ejector lever disposed between said parallel members pivoted at a point intermediate its length thereto, and adapted to move between said shelf members to discharge said articles from said shelf, and a retracting spring connected at one end to said frame at a point in advance of said lever, and at its other end to a portion of said lever below its pivot point, stop means for limiting the retraction of said lever by said spring, and means at the upper end of said lever adapted to be pushed or struck to effect the ejection movement of said lever.
4. In a dispensing device for articles of merchandise, in combination, a frame comprising a base, a pair of spaced parallel vertical members extending upwardly from said base, a horizontally disposed shelf member extending outwardly from the top of each of said vertical members, and adapted to successively support said articles, an eject or lever disposed between said parallel members pivoted at a point intermediate its length thereto, and adapted to move between said shelf members to discharge said articles from said shelf, and a retracting spring connected at one end to said frame at a point in advance of said lever, and at its other end to a portion of said lever below its pivot point, stop means for limiting the retraction of said lever by said spring, and means at the lower end of said lever adapted to be pulled to effect the ejection movement of said lever.
5. In a dispensing device for articles of merchandise, in combination, a frame comprising a base, a pair of spaced parallel vertical members extending upwardly from said base, a horizontally disposed shelf member extending outwardly from the top of each of said vertical members, and adapted to successively support said articles, an eject or lever disposed between said parallel members pivoted at a point intermediate its length thereto, and adapted to move between said shelf members to discharge said articles from said shelf, and a retracting spring connected at one end to said frame at a point in advance of said lever, and at its other end to a portion of said lever below its pivot point, stop means for limiting the retraction of said lever by said spring, and means at the lower end of said lever adapted to be pulled to effect the ejection movement of said lever.
6. In a dispensing device for articles of merchandise, in combination, a casing having a discharge opening in the front wall thereof, a shelf for successively supporting said articles adjacent said discharge opening, said shelf being provided with a slot, an ejector for said articles having a substantially central portion thereof pivoted at a point below said shelf, a plurality of peripherally spaced projections on said ejector, one of said projections adapted to move in said slot to eject articles forwardly of said device through said opening, another of said projections extending through an opening in the rear wall of said casing and adapted to be pushed for operating said ejector, a third projection also extending through said last named opening and adapted to be pulled for operating said ejector, a spring secured to a fourth one of said projections for urging said ejector toward retracted position, and a stop abutment on said ejector adapted to contact with a stationary portion of said device when said ejector is in said retracted position.
